UNITED STATES PATENT OFFICE.

WILEY D. COTTON, OF DARDANELLE, ARKANSAS.

MEANS FOR CURING SWEET POTATOES.

1,388,328.

Specification of Letters Patent. Patented Aug. 23, 1921.

Application filed May 8, 1920. Serial No. 379,836.

To all whom it may concern:

Be it known that I, WILEY D. COTTON, a citizen of the United States, residing at Dardanelle, in the county of Yell and State of Arkansas, have invented certain new and useful Improvements in Means for Curing Sweet Potatoes, of which the following is a specification, reference being had to the accompanying drawings.

10 This invention relates to means for curing sweet potatoes, and it is an object of the invention to provide a novel and improved means of this general character whereby air is blown through and under the potatoes 15 at the requisite temperature and in a manner whereby the moisture carried off by the air is prevented from condensing on ceiling of the housing structure.

Another object of the invention is to provide a novel and improved means of this general character including a building structure or house interiorly divided into a plurality of bins or sections and wherein a heating medium is provided above each 25 bin or section to maintain an even temperature.

An additional object of the invention is to provide a novel and improved means of this general character embodying a building structure having a plurality of sections or bins arranged therein for the potatoes to be treated whereby the air within the building structure and more particularly at the upper portion thereof may be caused to circulate in a whirling fashion and which is of 30 particular advantage to prevent the accumulation of condensation on the ceiling of the structure and whereby is effectively overcome a decided disadvantage.

40 The invention consists in the details of construction and in the combination and arrangement of the several parts of my improved means for curing sweet potatoes whereby certain important advantages are 45 attained and the device rendered simpler, less expensive and otherwise more convenient and advantageous for use, as will be hereinafter more fully set forth.

The novel features of my invention will 50 hereinafter be definitely claimed.

In order that my invention may be the better understood, I will now proceed to describe the same with reference to the accompanying drawings, wherein:

55 Figure 1 is a fragmentary diagrammatic

view in top plan of a means for curing sweet potatoes constructed in accordance with an embodiment of my invention, the building structure proper being omitted;

Fig. 2 is a sectional view taken substantially on the line 2—2 of Fig. 1;

Fig. 3 is an enlarged fragmentary view illustrating in detail a hallway nozzle and a floor nozzle; and

Fig. 4 is an enlarged fragmentary sectional view illustrating in detail a ceiling nozzle.

As disclosed in the accompanying drawings, S denotes a housing structure provided at predetermined points on its roof 1 with 70 the vents 2, of any desired construction, which provide means for exhausting the air within the housing structure S. Located within the structure S are the series of bins B arranged in a manner whereby the hallways 3 are provided. The upper portion of the interior of the structure S affords an air chamber with which each bin B communicates and each of said bins B is provided with a slatted floor 4 positioned a desired 80 distance above the floor F of the housing structure S with solid walls 5 separating adjacent bins so that if one bin is receiving warm air, said walls will prevent the air of one bin interfering with the other. The 85 front of each of the bins is also of slats and each of said bins B is divided into a plurality of compartments by the vertically disposed slatted walls 6. Each of said compartments has disposed substantially centrally thereof a vertically disposed nozzle 7, 90 preferably formed of slats.

P denotes a pipe line arranged exteriorly of the housing structure S and which leads from a suitable source of heated air and 95 which air is preferably forced through the pipe under the influence of a fan of any desired character. The pipe line P is arranged adjacent the upper portion of the structure and is provided with the laterally disposed 100 branch pipe lines P' which extend within the housing structure and longitudinally of the end hallways 3.

Extending from each of the branch pipe lines P' in opposite directions are the horizontally disposed pipes 8. Each of the pipes 8 overlies one or more compartments of the bins and above each compartment has interposed therein a nozzle 9 capable of rocking movement so that the same may be disposed 110

in different positions with respect to the pipe 8 as its axis. Interposed in the nozzle 9 is a valve or damper 10, preferably of a sliding type so that the discharge through each 5 of the nozzles may be controlled one independently of the other.

Depending from the pipes 8 and arranged at opposite sides of the hallways 3 are the pipes 11 which terminate below the floor F 10 of the housing structure. Interposed in each of the pipes 11 at a point in close proximity to the floor F is a horizontally disposed nozzle 12, also capable of rocking movement relative to the pipe 8 as its axis. Coacting with 15 each of the nozzles 12 is a sliding damper or valve 14 for controlling the discharge therethrough. The portion of each of the pipes 8 beneath the floor F constitutes a nozzle whereby the air may be delivered thereunder 20 as required and the flow through the lower end portion of each of said pipes 11 is under control of the sliding valve or damper 15.

The lower portion of each of the pipes 11 is also provided with a horizontally disposed 25 nozzle 16 and which extends a distance beneath the floor 4 of an adjacent bin B and the flow through said nozzle 16 is under control of a sliding valve or damper 17.

As the air is discharged through the nozzles 16, such air strikes the vertically spaced 30 pair of slats 18 arranged below the floor 4, said pair of slats converging in cross section toward the discharge end of the nozzle 16 and terminating in close proximity thereto. The slats 18 operate as a spreading medium 35 whereby the heated air discharged from the nozzle 16 is caused to come into contact or strike all of the potatoes at the bottom of a bin thereby assuring the proper 40 curing.

The nozzles 12 are adjusted to the angle as best preferred in practice and operate to assure a constant circulation or moving of the air within the housing structure while 45 the nozzles 9 may be disposed downwardly to direct the air directly upon the potatoes in the upper portion of the bins or in an upward direction to effect a circulation of air in the upper portion of the housing structure and to cause the same to pass out 50 through the vents 2 before the moisture carried by the air from off the potatoes can condense on the ceiling and drop back on the potatoes. It is to be understood that 55 all of the pipes within the housing are of material to radiate heat supplied by the air passing therethrough so that said pipes will be maintained substantially at the same temperature as the air passing therethrough and 60 serve as a further means for maintaining the requisite temperature within the housing structure. The nozzles 9 are turned downwardly particularly when the potatoes at the upper portions of the bin become cool 65 and damp as occasioned by the air passing

upwardly through the potatoes. If preferred, half of said nozzles 9 can be disposed downwardly and the remainder disposed upwardly, the latter number serving to effect the requisite circulation of the air in the upper portion of the housing structure to prevent condensation.

The various dampers or slides coacting with the nozzles serve to permit certain of the bins to cool down while the remainder 75 are still receiving the requisite warm air and when required, all of the dampers or valves except the valves or dampers 15 may be closed so that the full force of the air will be caused to be discharged below the floor F 80 so that said floor will be thoroughly dried in the event the same becomes damp. The hall nozzles 12 can be also adjusted as required to either blow the air up or down the hallway or to opposite sides of the hallway and 85 the nozzles 9 and 12 can also be so adjusted or positioned as to cause the air to circulate through the housing structure in a whirlwind fashion. In this latter arrangement, the ceiling nozzles and hallway nozzles at 90 one side of the housing structure are turned in one direction and the nozzles at the other side of the house are turned in the opposite direction. With this arrangement, it will be readily seen that the air will be whirled 95 around within the housing structure and cut through the vents 2 before condensation will occur on the ceiling.

As is illustrated in the accompanying drawings, it is to be noted that certain of 100 the bins are arranged in double rows and that a pipe line P' is arranged directly above such double row. This is of particular advantage as the damp air rising from the potatoes within such bins comes directly in 105 contact with a greater heating surface.

I also find it of advantage to have the slats 4 of each bin lower at the back. It is also to be understood that the slats are loose and can be readily removed when necessary 110 in order to remove accumulated dirt and to otherwise thoroughly clean out the bin. By having the slats 4 disposed on a downward incline or slant, the air will have a better or more effective pressure in the front portion 115 of the bin.

The lower portion of each of the pipes 11 is removable on account of the loose joint 11a. It is desired to have the lower portions of the pipes 11 removable to facilitate the 120 placing of the potatoes in the bins.

When desired, a supplemental nozzle 16a may be engaged with a nozzle 16. The nozzle 16a is provided with an angular discharge end portion so that the heated air 125 may be forced directly up through a nozzle 7 within a bin. The nozzle 16a is preferably secured to a nozzle 16 by a slip or loose joint so that the same may be applied or removed with convenience and facility. 130

When the nozzle 16^a is employed, the slats 18 which would otherwise coat with the nozzle 16 are removed.

From the foregoing description, it is thought to be obvious that a means for curing sweet potatoes constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

20 I claim:—

1. A means for curing potatoes embodying the combination with a house structure inclosing a plurality of bins and providing an upper chamber above said bins and hallways, said housing structure being provided with means for exhausting the air from the chamber, each bin communicating with said chamber, and air conduits within the upper portion of the housing and leading from a suitable source of supply, of nozzles interposed in said conduit and each having rocking movement about substantially a horizontal axis.

2. A means for curing potatoes embodying the combination with a house structure inclosing a plurality of bins and providing an upper chamber above said bins and hallways, said housing structure being provided with means for exhausting the air from the chamber, and each bin communicating with said chamber, air conduits within the upper portion of the housing and leading from a suitable source of supply; of nozzles interposed in said conduit and having rocking movement about substantially a horizontal axis, and conduits leading from said first named conduits and discharging below the bins, and substantially horizontally disposed nozzles interposed in said last named conduits and arranged within the hallways, said last named nozzles being adjustable about substantially a vertical axis.

3. A means for curing potatoes embodying the combination with a house structure inclosing a plurality of bins and providing an upper chamber above said bins and hall-

ways, said housing structure being provided with means for exhausting the air from the chamber, and each bin communicating with said chamber, air conduits within the upper portion of the housing and leading from a suitable source of supply; of nozzles interposed in said conduit and each having rocking movement about substantially a horizontal axis, and a controlling valve coacting with each of the nozzles.

4. A means for curing potatoes embodying the combination with a house structure inclosing a plurality of bins and providing an upper chamber above said bins and hallways, said housing structure being provided with means for exhausting the air from the chamber, and each bin communicating with said chamber, air conduits within the upper portion of the housing and leading from a suitable source of supply; of nozzles interposed in said conduit and having rocking movement about substantially a horizontal axis, conduits leading from said first named conduits and discharging below the bins, substantially horizontally disposed nozzles interposed in each of said last named conduits and arranged within the hallways, said last named nozzles being adjustable about substantially a vertical axis, and a controlling valve coacting with each of the nozzles.

5. A means for curing potatoes embodying the combination with a house structure inclosing a plurality of bins and providing an upper chamber above said bins and hallways, said housing structure being provided with means for exhausting the air from the chamber, and each bin communicating with said chamber, air conduits within the upper portion of the housing and leading from a suitable source of supply; of nozzles interposed in said conduit and each having rocking movement about substantially a horizontal axis, conduits leading from said first named conduits and discharging below the bins, substantially horizontally disposed nozzles interposed in said last named conduits and arranged within the hallways, each of said last named nozzles being adjustable about substantially a vertical axis, said last named conduits also discharging below the floor of the housing, and means for controlling said last named discharge.

In testimony whereof I hereunto affix my signature.

WILEY D. COTTON.
